UNITED STATES PATENT OFFICE.

NELSON WITTS, OF ALMA CITY, MINNESOTA.

ROTARY ENGINE.

SPECIFICATION forming part of Letters Patent No. 587,904, dated August 10, 1897.

Application filed January 13, 1897. Serial No. 619,075. (No model.)

To all whom it may concern:

Be it known that I, NELSON WITTS, a citizen of the United States, residing at Alma City, county of Waseca, and State of Minnesota, 5 have invented certain new and useful Improvements in Rotary Engines; and I do hereby declare the following to be a full, clear, and exact description of the invention, such as will enable others skilled in the art to which it 10 appertains to make and use the same, reference being had to the accompanying drawings, and to letters and figures of reference marked thereon, which form a part of this specification.

15 This invention relates to rotary engines, and more particularly to that class in which a revolvel disk having radially-movable pistons is used; and it has for its object certain 20 improvements whereby the construction is materially simplified and cheapened and the dimensions relatively to a given power considerably reduced.

25 In the accompanying drawings, Figure 1 is a side elevation of my improved engine, one of the heads being removed. Figs. 2 and 3 are like views of the two heads. Fig. 4 is a transverse section of the engine, taken on line x x of Fig. 1, as it appears when looking in the direction of arrows x' x' , said section being shown to an enlarged scale; and Fig. 5 is a perspective view of one of the radially-movable pistons.

30 The engine consists, essentially, of two heads, a piston-disk arranged between such heads and having radially-movable pistons, a shaft to which the piston-disk is secured, and means for supplying the motive fluid to and for exhausting the same from the engine.

35 The head or head-plate H has an opening o , 40 Fig. 2, for the engine-shaft and a segmental stepped portion h h^2 , whose inner faces are arcs of a circle having for center the center of the shaft-opening o . To the upper face of the higher portion h^2 of the stepped sector 45 and to a ledge h' , extending along the lower edge of the head H , is bolted fluid-tight the other head, H' , in the inner face of which is formed an irregular or cam groove h^3 . The 50 remaining portion of the head H may be constructed, as shown in Figs. 1 and 2, with a

hub portion h^4 and radial spokes h^5 , while the head H' is preferably made solid. Between these heads H and H' works the piston-disk P , which is secured to the engine-shaft S , that revolves freely in the opening o of head H 55 and in a corresponding opening o' in head H' . The piston-disk P is provided with a number of radially-arranged pistons p , that carry at their inner ends an antifriction-roller r , projecting into the aforesaid cam-groove h^3 in 60 head H' . The piston-disk P is of such diameter relatively to the segmental raised portion h^2 on the head H as to leave a space s between the periphery of said disk and the inner arcuate face of the raised portion h^2 , as 65 shown more plainly in Fig. 1, except at the lower end, where said portion h^2 is extended inwardly into contact with the periphery of the disk P , as shown, to form an end wall 2 for said space s .

70 As shown in Figs. 1 and 2, the raised portion h^2 is recessed from its inwardly-projecting end 2 to a point 3, whereby the inner portion 4 of the space s is enlarged for purposes hereinafter referred to, the motive-fluid admission-pipe 4^x being arranged to extend through said inwardly-extended portion 2. The cam-groove h^3 is of such a form as to project the pistons p from the disk P the moment said pistons have cleared the end 80 wall 2 of the space s , in which position they remain until they reach or are about to reach the opposite end 4^a of said space, when said arms are again retracted flush with the periphery of the disk P . It will thus be seen 85 that the outer weighted end p' of the pistons p during the time they are projected and as soon as they reach the point 3 of the aforesaid space s form, with the end wall 2, a closed motive-fluid chamber, the inner portion 4 of which is enlarged. The object of enlarging the inner end of the motive-fluid space s is to avoid back pressure upon the projected end p' of a piston-arm p after entering the motive-fluid passage s , the pressure within the enlarged part 4 of said space acting equally upon all sides of the projected end p' of the piston whether the motive fluid— 90 as steam, water, or air—is admitted to the enlarged portion 4 of the space s through the 95 100

end wall 2 thereof or at any other point of said enlarged portion, as will be readily understood.

In the described construction of engine the motive fluid acts at all times upon a single piston p to revolve the disk P , and therethrough the shaft S , and before the piston has cleared the outer space s the next succeeding piston will have reached the point 3 10 or outer end of the enlarged portion of said space, so that when the preceding piston clears the space s the motive fluid between the two will exhaust.

In order to avoid the noise due to the sudden liberation of steam, for instance, confined between two pistons in the narrower portion of the space s , I prefer to form an exhaust-channel 8, as shown in dotted lines in Fig. 1, in the vertical face of the raised portion h^2 , the depth of which channel is gradually increased outwardly to the outer end of such vertical face or to the outer end 4^a of space s , whereby the motive fluid is gradually exhausted.

25 The piston-disk works, of course, fluid-tight between the raised portion h^2 of the segmental stepped portion on head H and between the inner face of head H' , while the outer winged end p' of the pistons p works 30 fluid-tight along the under face of the raised portion h^2 of said stepped portion and between the inner faces of the head H' and raised portion h of head H .

In the drawings I have shown the piston-disk P constructed in the form of a wheel, and with the open construction of the head H a very light though very powerful engine is obtained.

Inasmuch as the rotation of the piston-disk 40 P cannot be reversed it will be necessary to provide two engines on the same shaft, their arrangement thereon being reversed, of course, whenever it is desirable to reverse the direction of rotation of such shaft. On 45 the other hand, instead of exhausting the motive fluid directly into the atmosphere, suitable means may be provided at the exhaust end 4^a of the motive-fluid space s to catch the exhausted motive fluid and conduct it to a 50 point distant from the engine. In this case the upper half of the head-plate H proper may be made solid and the exhaust taken through a suitable opening therein at or

proximate to the exhaust end 4^a of the space s , which end would of course be closed or 55 merge into an exhaust-chamber.

It will be seen that the alternate projection and retraction of the pistons p is effected positively or mechanically by the cam-groove h^3 and not by means of motive fluid, as has heretofore been proposed, thereby rendering their operation more certain. On the other hand, the actual motive-fluid space is of a very limited area, so that the expense of truing the surfaces to fit or work fluid-tight is greatly 60 65 reduced, while the packing of the engine-shaft is entirely dispensed with, thereby doing away with a great deal of friction.

The piston-disk P is properly supported on the shaft S , between the heads H and H' , by 70 providing said disk with a suitably-enlarged hub p^2 , fitting snugly between the said heads.

The engine may be secured in any desired manner to a floor or other foundation, to which end the heads H and H' may be provided 75 with foot-flanges, as shown in Fig. 4.

Having thus described my invention, what I claim as new therein, and desire to secure by Letters Patent, is—

A rotary engine comprised of two head-plates, H , H' , the head H being constructed with a hub portion having segmental spokes and a segmental stepped portion whose inner faces are arcs of a circle having for center a shaft-opening formed in said hub, a ledge 85 formed on the lower edge of the head, the head H' bolted to said ledge and segmental stepped portion forming a fluid-space beneath the stepped portion, a cam and a shaft-bearing formed in said head, a shaft revoluble in said 90 bearings, a piston-disk on the shaft between said heads, pistons movable in said disk, arms on the pistons carrying antifriction-rollers working in the cam-groove whereby said pistons are projected into the fluid-chamber on 95 entering and withdrawn upon leaving the chamber, substantially as and for the purpose specified.

In testimony that I claim the foregoing as my invention I have signed my name in presence of two subscribing witnesses.

NELSON WITTS.
